UNITED STATES PATENT OFFICE.

AUGUSTIN REY, OF STAINS, FRANCE.

PUMP.

Application filed October 6, 1924, Serial No. 741,988, and in France October 8, 1923.

This invention relates to improvements in the construction of externally adjustable constant delivery pumps, and more particularly, but not exclusively, of the type in which there is a rotary pump barrel whose rotation regulates suction and delivery, and in which works a number of plunger pistons.

These improvements have for their object to obtain absolute regularity of delivery, and, by almost completely eliminating wear at the points of attachment of the pistons, to effect substantial economies in maintenance.

The pump is particularly useful for feeding liquid under pressure, for transmitting power, lubricating engines and joints, as well as for machines employed to displace liquids or gases (compressors, pumps and the like).

According to this invention the pump barrel, surrounded by a casing, has in it chambers which are parallel to the axis of the barrel, while the pistons or plungers working in the chambers are connected to a block movable in a head, fast with the casing, means being provided for inclining the block about an axis at right angles to the axis of the barrel, and for rotating either the barrel or the casing.

The heads of the pistons are connected to the block by a universal joint, while provision is made for movements of the coupling members to compensate for the difference in the diameters of the elliptical path described when the block is inclined to the axis of rotation.

To adjust the delivery of the pump while running, means such as a screw and universal joint may be provided for altering the inclination of the block.

The invention is illustrated in the accompanying drawings, in which Figure 1 is a partial longitudinal section of a three piston pump, Figure 2 a section on the line X—X of Figure 1, Figures 3 and 4 respectively a side elevation and an end view of the pump head. Figure 5 shows a detail.

Referring to Figures 1 and 2, 1 is a cylindrical pump casing, one end 2 of which is formed to receive a continuation 4 of the distributing barrel 5, while the other end of the pump casing is provided with a head 3.

6 and 7 are respectively the suction and delivery ports, which are alternately placed in communication with the barrel chambers

through grooves 6' 7', separated by small solid portions formed on the casing 1, or on an inner sleeve thereof.

Barrel 5 is, as above set out, provided with a prolongation 4, whereby it can be rotated by mechanical means, such as a pulley 8, or by a toothed wheel, or by the direct drive from an engine.

Barrel 5 is bored at 9 to form a suitable number of chambers, as illustrated, three, in which work plungers 10. The chambers 9 are parallel to the axis of rotation of the barrel and communicate through passages 11 with the grooves 6', 7'.

Pumps of this type are known, but other similar pumps have a stationary barrel and a movable casing. Various means have been proposed for reciprocating the pistons. Thus, it has been proposed to move the head of the piston by a plate whose axis of rotation is inclined to the axis of the barrel. It will be seen that with this arrangement, when the barrel is rotated, the projection of the point of abutment of each piston head on the axis of the barrel is given an alternating movement, but if the plate merely acts on the piston heads without a mechanical joint between them, the pistons will only move inwards and will not return; to enable the pistons to return, they must be connected to the plate by a joint such that a piston moving inwards will, by the pressure of the plate, move another piston connected to the first said piston.

In arrangements previously proposed, the parts wear rapidly; moreover, delivery is not absolutely constant.

The mounting of the pistons in the manner to be described, and which forms the essence of the invention, avoids such wear, or at least considerably reduces the wearing effect, whereby a pump may continue in use for a much longer time without undergoing repair.

The head 3 is internally of hemispherical shape, as shown at 12, and is provided with a central opening 13. Externally, head 3 is prolonged by two plates 13', Figure 4, which are cast with the head.

14 is a block provided with a spherical portion concentric with the cavity 12 of head 3; the block 14 is, moreover, provided with a prolongation 15 having two flats which slide in the opening 13 between the plates 13'.

The outer edges of plates 13' are circular,

so that block 14 can be set in any position and there locked by clamping a plate 16 against plates 13' by a nut 17 screwing on the outer end of prolongation 15. The setting of block 14—15 may be effected in any suitable manner. As illustrated, in Figures 3 and 4, it is effected by a milled head 21, a screw rod 18, (in a slot 19 formed in one plate 13') acting upon a pin 20 which engages prolongation 15. The displacement given by screw rod 18 may be made very accurate by the provision of a fixed scale 22, and movable pointer 23, or vice versa, so that it is possible, while the pump is in action, to adjust the inclination of block 14 to the axis of casing 1, by unscrewing nut 17, bringing this head into a new position and then again screwing up.

Block 14 is provided with a central recess 14' for receiving a nut 24; 25 is a plate, 26 a block, and 26' a prolongation thereof, while nut 24 is carried by the prolongation 26' and screws against plate 25. A ball bearing may be interposed between plate 25 and block 26, in which the heads of pistons 10 are mounted. As plate 25 is rigidly fixed to the block 14, it will be seen that block 26 is, to some extent, fast with it, and will follow any movement given to it by the screw 18, but it can also turn with mild friction around axis 26'. Block 26 is of cylindrical shape, but can move freely in the recess in head 3 and in casing 1.

The heads 30 of the pistons 10 are connected to block 26 by ball joints formed of a pin 27 passing through piston rod 10' and ball segments 28 arranged in a socket 29 formed in block 26; pin 27 can thus rotate in socket 29.

40 The positions of pin 27 and segments 28 may be reversed from that shown in Figure 1, i. e., pin 27 may be radial and segments 28 tangential to the block 26.

45 It will be seen that in the neutral position of block 14, i. e., when the axis of prolongation 15 is coincident with the axis of barrel 15, the rods 10' are at right angles to the plane of the base of block 26 but when block 14 is inclined (and therefore also 50 block 26) rods 10' must position themselves; for this purpose each socket 29 is extended by a recess 29'.

55 When, however, block 26 is displaced, the heads of the piston will no longer, as in the neutral position, describe a circle; it is therefore necessary to allow for the difference between the large diameter (which remains constant) and the small diameter which depends on the angle of prolongation 60 15 to the general axis, so that the attachment heads 30 can slide slightly upon the pins 27 which connect them to the block 26.

65 The spaces 31 between the head 30 and segments 28 provided with this object, are of course a function of the diameter of the

barrel, or with greater exactitude, of the distance of the pistons to the general axis and of the inclination which can be given to prolongation 15.

Moreover, the segments 28 slide slightly 70 in socket 29, these movements compensating for the deviation from a circular path described by the heads 30.

The apparatus operates as follows:

When barrel 5 is rotated by pulley 8, pistons 10 are rotated and in their turn drive plate 26 which turns about its axis 26'. If axis 26' is inclined to the axis of rotation of the barrel, the heads of the pistons move in and out of the barrel to perform 80 the suction and delivery strokes, the chambers in the barrel being automatically placed in communication with the inlet and exhaust ports 6 and 7 by the grooves 6' and 7'.

When the barrel is stationary, and casing 85 1 and its head 3 are rotated, the block 26 will be reciprocated and the block 14 will turn about the axis 26', thus providing the same effect.

It will be seen that the movements take 90 place quietly; each piston acts for itself, its head 30 turning about its pin 27, and the segments 28 in their socket, the sliding movement of head 30 on its pin 27, and that of segments 28 in their socket 29, always taking 95 place between parallel surfaces.

It will be seen that serious wear of the parts cannot take place, whereby stoppages are reduced to a minimum.

The set of barrels 5 in casing 1 for the 100 unmasking of passages 6 and 7 allows of always being at delivery pressure; in order, however, to compensate for possible slight pulsations, the delivery passage 7', for example, may, as illustrated in Figure 5, be 105 provided with a radial outlet 33 closed by a flexible membrane 32 or any other elastic liquid tight part, not attacked by the liquid pumped.

I claim:

1. In a pump barrel, the combination with a pump casing of a pump barrel having chambers therein parallel to the axis thereof, a rotatable member suitably supported within the pump casing for rotation about an axis coincident with the axis of the pump barrel, said member having spherical sockets therein, pistons working in the chambers of the said pump barrel and having attachment heads which fit within corresponding sockets of the rotatable member, a pin in each socket passing loosely through the attachment head fitted therein, ball-segments at the ends of the pin and free to slide relatively to the socket, said ball-segments being spaced from the attachment head to allow the same to slide on the said pin, means for adjusting the rotatable member so that the inclination of its axis may be varied in relation to the axis of the bar- 125

rel, and means for rotating the pump barrel.

2. In a pump, a rotatable pump barrel provided at one end with a prolongation whereby it can be rotated by mechanical means, said barrel having chambers parallel to the axis thereof, a pump casing having bearing means at one end to receive the said prolongation and having a hemispherical seat at the other end, an adjustable member 5 slidably fitted to the said seat, a rotatable member pivoted to the said adjustable member for rotation about an axis coincident to the axis of the pump barrel, pistons working in the chambers of the pump barrel and having flexible connection with the said pivotally mounted member, means for moving the said adjustable member relatively to its seat for inclining the axis of the rotatable member to the axis of the pump barrel, and means for locking the adjustable member in the position to which moved.

3. In a pump, the combination with a pump casing having a hemispherical seat at one end, a rotary pump barrel within the

casing having piston chambers, pistons operating in the said chambers, a cylindrical member having the said pistons connected thereto, a hemispherical member slidably supported on the said seat and having the said cylindrical member pivoted thereto for 25 rotation about an axis coincident to the axis of the pump barrel, said hemispherical member having a prolongation extending through the seat and exteriorly of the pump casing, spaced guide members between which 30 the said prolongation extends, said guide members having their outer edges curved in conformity with the curvature of the said seat, means for moving the said prolongation to incline the said cylindrical and hemispherical members with respect to the axis of the pump barrel, and locking means carried by 35 said prolongation and being adjustable into binding engaging with the said curved outer edges of the guide members to hold the said 40 cylindrical and hemispherical members in their adjusted position.

AUGUSTIN REY.
